DESIGN FOR A WHEELED TOY ANIMAL

Harry Sebel, London, England

Application May 16, 1946, Serial No. 129,760

Term of patent 14 years

(CL. D34—2)

To all whom it may concern:

Be it known that I, Harry Sebel, a subject of the king of Great Britain, residing at London, England, have invented a new, original, and ornamental Design for a Wheeled Toy Animal, of which the following is a specification, reference being had to the accompanying drawing, forming part thereof.

Fig. 1 is a front perspective view of a wheeled toy animal showing my new design;

Fig. 2 is a rear perspective view of the toy animal referred to in the preceding paragraph.

I claim:

The ornamental design for a wheeled toy animal, as shown.

HARRY SEBEL.
